UNITED STATES PATENT OFFICE.

EDWIN WOODWARD, OF STRYKER, OHIO.

HAY-CARRIER.

SPECIFICATION forming part of Letters Patent No. 352,075, dated November 2, 1886.

Application filed February 6, 1886. Serial No. 191,094. (No model.)

To all whom it may concern:

Be it known that I, EDWIN WOODWARD, of Stryker, county of Williams, and State of Ohio, have invented a new and useful Improvement 5 in Transferring Mechanism for Hay-Carrier Guide-Pulleys, of which the following is a full, clear, and exact description.

Reference is to be had to the accompanying drawings, forming a part of this specification, 10 in which similar letters of reference indicate corresponding parts in all the figures.

Figure 1 is a side elevation of my improved transferring mechanism. Fig. 2 is a sectional side elevation of a part of the same. Fig. 3 is 15 a sectional end elevation of the same, taken through the line *x x*, Fig. 2.

The object of this invention is to provide a mechanism for transferring hay-carrier guide-pulleys from one end of a barn to the other, 20 and which shall be so constructed that the transferring can be done easily, quickly, and without any climbing.

The invention consists of the construction and combination of the various parts of the 25 transferring mechanism, as will be hereinafter fully described.

Are two plates which are designed to be secured to the opposite ends of a barn, and upon which are formed studs B. The outer 30 ends of the studs B are connected by a wire, C, to form a way for the passage of the sleeves, hereinafter described, from one stud to the other.

Upon one of the studs B is placed a sleeve, 35 D, the ends of which are beveled upon their inner sides, and to the middle part of which are attached downwardly-projecting lugs E, to receive the guide-pulley, as shown in dotted lines in Fig. 1.

Upon the sleeve D is placed a sleeve, F, 40 which is made a little shorter than the sleeve D, and is slotted for the passage of the lugs E, the said slot being made three-quarters of an inch (more or less) longer than the width of the 45 said lugs E, to allow the said sleeve F to have a short longitudinal movement upon the interior sleeve, D. The ends of the exterior sleeve, F, are beveled, as shown in Figs. 1 and 2, and to the said ends are attached the ends of ropes 50 G, which pass around pulleys H, pivoted to lugs I, formed upon the plates A below the studs B.

Upon the plates A, above the studs B, are formed lugs J, to which are pivoted hooks K, to engage with the outer ends of the interior 55 sleeve, D, and hold it in place upon the studs B when the guide-pulley is being used. The outer ends of the hooks K are beveled, as shown in Figs. 1 and 2, so that the said hooks will be raised by the beveled ends of the exterior 60 sleeve, F, when the sleeves D F are drawn upon the studs B.

Upon the upper corners of the rear ends of the hooks K are formed projections L, which, when the said hooks are raised, come in contact with the ends of the plates A and prevent 65 the said hooks from being swung back too far.

Upon the lower corners of the rear ends of the hooks K are formed prongs M, for the beveled ends of the exterior sleeve, F, to strike 70 against to throw the said hooks downward to engage with the ends of the interior sleeve, D, and lock the said sleeves in place upon the studs B.

Upon the lower side of the forward parts of 75 the hooks K are formed inclines N, for the beveled ends of the sleeve F to engage with, when the said sleeve is drawn outward, to raise the said hooks from the ends of the interior sleeve, D, to allow the said sleeve to be drawn off the 80 studs B.

With this construction, when the guide-pulley is to be transferred from one end of the barn to the other, the rope G is pulled upon, the first effect of which is to draw the exterior sleeve, 85 F, forward upon the sleeve D and raise the hook K, and the two sleeves then move together along the wire C to the other stud B, when they are caught and held by the hook K until again released by drawing upon the other 90 rope G. The ropes G are led into such positions that they can be conveniently reached and operated from the floor or other desired position.

Having thus fully described my invention, I 95 claim as new and desire to secure by Letters Patent—

1. The combination, with the horizontal stud, a sliding sleeve on the said stud, lugs projecting from said sleeve, an exterior slotted sleeve 100 upon the first-mentioned sleeve, the lugs passing loosely through the said slots, of the pivoted hook extending lengthwise across the outer sleeve and engaging the end of the inner

sleeve, whereby in the forward movement of the outer sleeve the hook will be disengaged from the inner sleeve, substantially as set forth.

2. A transferring mechanism for hay-carrier guide-pulleys, constructed substantially as herein shown and described, and consisting of the plates A, provided with studs B, connected by a wire, C, the interior sleeve, D, having its ends beveled upon the inner side and provided with lugs E to carry the guide-pulleys, the exterior sleeve, F, having its ends beveled upon the outer side and having a slot for the passage of the lugs E, the ropes G, attached to the exterior sleeve, F, and their pulleys H, and the hooks K, having projections L and prongs M upon their rear end and inclines N upon their lower sides, whereby the guide-pulley can be readily moved from one end of the barn to the other, as set forth.

20 3. The combination, with the stud B and

hook K, provided with the prong M and incline N, of the interior sleeve, D, provided with lugs E, and the apertured sleeve F, having its ends beveled, substantially as shown and described, whereby the said hook will be 25 thrown into engagement with and disengaged from the interior sleeve.

4. A transferring mechanism for hay-carriers, consisting of the plate A, carrying stud B, fitted to receive a connecting-wire, and provided with a pivoted hook, K, and a pulley, H, the sleeve D, provided with lugs E, and the apertured sleeve F, mounted on sleeve D, having its ends beveled and fitted for attachment of an operating-rope, all constructed and combined substantially as shown and described.

35 EDWIN WOODWARD.
